UNITED STATES PATENT OFFICE.

JACKSON FLECKENSTEIN, OF GRAND RAPIDS, MICHIGAN, ASSIGNOR TO FLECKENSTEIN VISIBLE GASOMETER COMPANY, OF GRAND RAPIDS, MICHIGAN, A CORPORATION OF DELAWARE.

DESIGN FOR A LIQUID-DISPENSING APPARATUS.

57,426.

Specification for Design.

Patented Mar. 29, 1921.

Application filed November 4, 1919. Serial No. 335,746. Term of patent 14 years.

To all whom it may concern:

Be it known that I, JACKSON FLECKENSTEIN, a citizen of the United States, residing at Grand Rapids, in the county of Kent and State of Michigan, have invented a new, original, and ornamental Design for a Liquid-Dispensing Apparatus, of which the following is a specification, reference being had to the accompanying drawing, forming part hereof.

The figure is a perspective view of a liquid dispensing apparatus embodying my new design.

I claim:

The ornamental design for a liquid dispensing apparatus, as shown.

JACKSON FLECKENSTEIN.
